United States Patent Office

Des. 179,063
Patented Oct. 30, 1956

179,063

DRESS

Rose N. Choolfain, Belmont, Mass.

Application August 7, 1956, Serial No. 42,534

Term of patent 3½ years

(Cl. D3—26)

FIG. 1

The bow is formed of a strip of material secured along the edge of the collar and extending freely beyond with the bow secured at its knot near the edge of half of the bodice opening; the other free end is secured near the edge of the other half of the bodice opening.

I claim:

The ornamental design for a dress, as shown and described.
